UNITED STATES PATENT OFFICE

ALANSON KEMP RAMSDELL, OF OLD ORCHARD, MAINE.

APPARATUS FOR PORTABLE SLEIGHS.

No. 805,318.

Specification of Letters Patent.

Patented Nov. 21, 1905.

Application filed May 5, 1905. Serial No. 259,075.

To all whom it may concern:

Be it known that I, ALANSON KEMP RAMSDELL, a citizen of the United States, residing at Old Orchard, in the county of York and

5 State of Maine, have invented certain new and useful Improvements in Apparatus for Portable Sleighs; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to new and useful improvements in sleighs and mechanism for propelling the same; and the object of the invention is to produce a simple and efficient means whereby a motor of any kind adapted 20 for the purpose may be employed for driving an operating-wheel having spurs about its circumference adapted to cut into the surface of the snow or ice for the purpose of driving the sleigh.

25 My invention consists in various details of construction and in arrangements of parts, which will be hereinafter fully described and then specifically defined in the appended claims.

30 My invention is illustrated in the accompanying drawings, which, with the letters of reference marked thereon, form a part of this application, and in which—

Figure 1 is a side elevation of my improved sleigh. Fig. 2 is a bottom plan view. Fig. 3 is a top view, and Fig. 4 is a vertical sectional view taken on line 4-4 of Fig. 3.

Reference now being had to the details of the drawings by letter, A designates the rear 40 bob of the sleigh, and A' the front bob, the rear bob carrying a bolster B and the forward bob a bolster B'. Said bolsters are preferably connected each to its respective bob by pivotal connection, as shown, and projecting from the rear of the bolster B' is a segment-gear C, the teeth of which are adapted to mesh with a gear-wheel D, which is fixed to the vertically-rotating steering-post E, which has a hand-wheel E', fixed thereto at any convenient location to the operator. A fifth-wheel F rests upon the disk F', which is carried by the bolster B', and a cross-piece H is fastened to the fifth-wheel F and supports the platform K, on which the body of the sleigh rests. A pivot-pin or king-bolt H' fastens

the forward end of the platform to the bolster B', allowing the front bob and the segment which moves with the bolster B' to move therewith.

Pivots mounted upon the ears b, which are fastened to the bolster B, is a rack O, having recesses O' for the reception of said lugs b, and O' designates pins carried by the rack O and passing through apertures in the lugs b. The opposite sides of said rack taper forward 60 and carry in suitable bearings a shaft Q, which has fixed thereto the propelling-wheel J, having spurs J' about its circumference. A counter-shaft I is mounted in suitable bearings upon said rack, and a sprocket-wheel I' 70 is fixed to said shaft I, and I' designates a sprocket-chain passing about the sprocket-wheel I' and the sprocket-wheel Q', which is fixed to the shaft Q. A yoke-shaped brace N is fastened to the inner edges of the side pieces 75 of the rack and securely brace the same. Springs G are fastened to the under sides of the strips K² of the platform, and their free ends bear against the upper face of said rack, the purpose of which springs is to normally 80 hold the driving-wheel against the surface of the snow or ice upon which the sleigh is to be propelled.

S designates a shaft which is mounted in the bearings S' upon the platform of the sleigh, 85 and S² designates chains the forward ends of which are fixed to the shaft S and about which they are adapted to wind and, extending rearward, pass over the pulleys S³, which are mounted upon the platform of the sleigh, and 90 their lower ends are secured to said rack, near the forward end thereof.

T designates a handle which is pivotally mounted upon the shaft S and carries a pawl T', designed to engage the teeth of the ratchet-wheel T², which is fixed to the shaft S. By the provision of said lever it will be observed that means is provided for rotating the shaft S when it is desired to raise the rack and driving-wheel carried thereby.

Pivotally mounted upon the knees of the rear bob are the brake-levers W, the upper ends of which are pivotally connected to rods W', the forward ends of which are pivotally mounted upon the arms V, which project 105 from the shaft V', which latter is journaled in suitable bearings upon the under side of the platform of the sleigh. A foot-lever V² is also fixed to the shaft V' and is so positioned that it will be convenient for an oper- 110

ator to depress the same when he desires to cause the brakes to cut into the surface of the snow or ice, as may be desired.

A suitable motor X is mounted upon the 5 platform and has connection with a sprocket-wheel X', mounted upon the shaft I, and a second sprocket-wheel Y, fixed to the shaft I, has a sprocket-chain Y' passing about the same and also about said sprocket-wheel X', 10 whereby a rotary movement may be imparted to the shaft I and thence transmitted to the driving-wheel, as will be readily understood.

From the foregoing it will be observed that 15 a simple and efficient apparatus is provided for driving a bob-sleigh and one in which the steering and brake apparatus may be conveniently actuated by the operator at all times.

While I have shown a particular form of 20 apparatus illustrating my invention, it will be understood that I do not confine myself to the exact details of construction shown, but may vary the same, if desired, in various ways without in any way departing from the spirit of the invention.

25 Having thus fully described my invention, what I claim as new, and desire to secure by Letters Patent, is--

1. A motor-sleigh comprising, in combination with the bobs, a platform connecting the

same, a driving-wheel, a pivotally-mounted 30 rack on which said wheel is mounted, springs secured to the platform of the sleigh and bearing against the rack carrying said driving-wheel, a shaft mounted upon the platform, chains adapted to wind upon said shaft 35 passing over suitable pulleys and connected with said rack, and means for rotating said shaft, as set forth.

2. A motor-sleigh comprising, in combination with the bobs, a platform connecting the 40 same, a driving-wheel, a pivotally-mounted rack on which said wheel is mounted, springs secured to the platform of the sleigh and bearing against the rack carrying said driving-wheel, a shaft mounted upon the platform, chains adapted to wind upon said shaft 45 passing over suitable pulleys and connected with said rack, means for rotating said shaft, pivotal brake-levers mounted upon the sleigh, a brake-shaft journaled in suitable bearings 50 upon the sleigh, and rod connections between said brake-shaft and brake-levers, as set forth.

In testimony whereof I hereunto affix my signature in presence of two witnesses.

ALANSON KEMP RAMSDELL.
